(57) **CLAIM**

The ornamental design for a support stand as shown and described.

DESCRIPTION

FIG. 1 is a top perspective view of a support stand showing my new design;

FIG. 2 is a bottom perspective view thereof;

FIG. 3 is a front elevational view of the support stand, the opposing rear elevational view of which is identical thereto; FIG. 4 is a left side elevational view of the support stand, the opposing right side elevational view of which is identical thereto;

FIG. 5 is a top plan view of the support stand; and, FIG. 6 is a bottom plan view of the support stand.

The support stand is shown with a symbolic break in its length. The appearance of any portion of the article between the break lines forms no part of the claimed design. The broken lines lying horizontally across the undersides of the cross-rails and vertically across the side faces of the cross-rails denote boundaries between unclaimed outer ends of the cross-rails, and claimed remainders of the cross-rails. All other broken lines denote unclaimed portions of the support stand, including inside edges of the legs at elevations at and below the cross-rails, and a recessed fastener hole and associated screw fastener at a central crossing point of the cross-rails. All broken lines, and the boundaries and unclaimed portions denoted thereby, form no part of the claimed design.

1 Claim, 3 Drawing Sheets
